UNITED STATES PATENT OFFICE.

HENRY UNTERMEYER, OF NEW YORK, N. Y.

DESIGN FOR A WATCH-CASE.

SPECIFICATION forming part of Design No. 12,485, dated September 20, 1881.

Application filed August 4, 1881. Term of patent 3½ years.

To all whom it may concern:

Be it known that I, HENRY UNTERMEYER, of the city, county, and State of New York, have invented a new and improved Design for 5 Watch-Cases, of which the following is a specification.

The photographic illustration is a front elevation of my newly-designed watch-case.

The leading feature of my design consists in 10 the representation of a locomotive-engine and tender upon a railroad-track with ornamental plants in the foreground.

A is the lid of the watch-case, upon which is represented a locomotive-engine, B, and 15 tender C upon a railroad-track, D. In the foreground is represented a growth of ornamental plants, E, and the whole is surrounded by a ring of dots, F, and an ornamental border, G.

Having thus described my invention, I claim 20 as new and desire to secure by Letters Patent—

1. The design for a watch-case herein shown and described, the same consisting of the representation of a locomotive-engine and tender upon a railroad-track, with ornamental plants 25 in the foreground.

2. The design for a watch-case herein shown and described, the same consisting of the representation of a locomotive-engine and tender upon a railroad-track, with ornamental plants 30 in the foreground, and surrounded by a ring of dots and an ornamental border.

HENRY UNTERMEYER.
